UNITED STATES PATENT OFFICE.

PIERRE DELORME, JR., OF PARIS, FRANCE.

AUTOMATIC MOLD FOR PIECES IN GLASS, &c.

SPECIFICATION forming part of Letters Patent No. 608,141, dated July 26, 1898.

Application filed May 29, 1897. Serial No. 638,784. (No model.) Patented in France January 29, 1897, No. 263,577; in Belgium April 28, 1897, No. 127,902; in Austria April 29, 1897, No. 2,909; in England April 29, 1897, No. 10,691; in Switzerland May 1, 1897, No. 14,533, and in Italy May 5, 1897, No. 44,632.

To all whom it may concern:

Be it known that I, PIERRE DELORME, Jr., a citizen of the Republic of France, and a resident of 85 Rue Charlot, Paris, France, have 5 invented certain new and useful Improvements in Automatic Molds for All Pieces in Glass or Ceramic Material, (for which I have obtained Letters Patent in France, No. 263,577, dated January 29, 1897; in England, No. 10,691, dated April 29, 1897; in Switzerland, No. 14,533, dated May 1, 1897; in Italy, No. 44,632, dated May 5, 1897; in Belgium, No. 127,902, dated April 28, 1897, and in Austria, No. 2,909, dated April 29, 1897,) of which the 10 following is a specification, reference being had to the accompanying drawings, forming a part thereof, in which similar letters of reference indicate corresponding parts.

This invention relates to an automatic 20 mold for the production of various articles of glassware or like material having holes or hollow portions therein.

My invention consists in the novel construction and assemblage of the operating parts of 25 the mold, as will be fully described herein and specifically set forth in the annexed claim.

In the accompanying drawings, Figures 1, 2, and 3 are longitudinal sections of different pieces produced by my mold. Fig. 4 is a 30 transverse elevation of a mold adapted to produce the piece shown in Fig. 1, the mold being open. Fig. 5 is an end elevation, partly sectional. Fig. 6 is a mold for producing the 35 piece shown in Fig. 2. Fig. 7 is the mold for producing the piece shown in Fig. 3.

Referring to the drawings, A is a base of 40 cast-iron upon which the mold is mounted. This mold is formed of two pieces D E, jointed together by a hinge C. A bolt d passes through the piece E and is adapted to turn freely therein. To its outer end a lever d' is 45 fixed and by means of which it is operated, and its other end is turned over, forming a hook adapted for engagement with the rear wall of the piece D when the mold is closed, thus holding the parts D and E closely together.

A shaft B, mounted in suitable journals b in the base A, is adapted to be oscillated by 50 means of the lever C', which is fixed to one

end thereof. Upon this shaft B are fixed the cam-slotted collars F, G, and H. Operated, respectively, by the eccentrics F, G, and H are the levers f, g, and h, each fulcrumed to suitable lugs mounted upon the base. 55

The upper or free ends of the levers f, g, and h engage with and operate the reciprocating members f', g', and h', respectively. Said reciprocating members work in suitable bearings supported by the main frame. A 60 projecting spur f², fixed to the member f', is adapted to form the hole f³ in Fig. 1. The projecting spur h², fixed to the member h', produces the hole h³ in Fig. 1 and the spur g², fixed to the member g', produces the hole g³ 65 in Fig. 1.

An upwardly-projected semicircular wall M on the frame of the machine at its top forms one side of the cup L and a similar projection of the part E forms the opposing side 70 wall of said cup. The hole m communicates between said cup and mold.

The parts being in position, as shown in Fig. 4, the member E is raised and locked to the member D. The molten glass is then 75 poured in the cup L, from which it flows through the hole m into the mold. When cool, the shaft B is operated by means of the lever C', the parts moving in the direction of the arrow. Through the medium of the cam-slotted collars and levers the parts f², g², and h² are withdrawn from the mold, the mold 80 unlocked and opened, and the glass formed will then fall out. A reverse operation again puts the mold in condition for another casting. 85

In Figs. 6 and 7 the pieces formed are not the same, but are obtained by the same means, the molds and forms only being different.

In Fig. 6 the lever f actuates a semicircular 90 form f⁴, which produces the hole f³ in Fig. 2.

In Fig. 7 the spur g⁴ forms the hole g³ in Fig. 3, while the hole g⁶ in Fig. 3 is formed by the part n, which is operated by hand.

Any and all pieces containing a hollow cavity or hole may be cast with my mold of any molten substance, and it is obvious the operating parts may be changed without departing from the spirit of my invention. 95

Having thus described my invention, what 100

I claim as new, and desire to secure by Letters Patent, is—

In a machine for molding molten material, a shaft, cam-slotted collars fixed thereon, levers actuated by said collars, forms operated by said levers, a jointed mold hinged together, and means for locking the parts of said mold securely together, substantially as shown and described.

In testimony that I claim the foregoing as to my invention I have signed my name, in presence of the subscribing witnesses, this 23d day of March, 1897.

PIERRE DELORME, JUNIOR.
